UNITED STATES PATENT OFFICE.

LOUIS J. FLINT, OF DETROIT, MICHIGAN, ASSIGNOR TO GRIP NUT COMPANY, OF CHICAGO, ILLINOIS, A CORPORATION OF ILLINOIS.

GRIP-NUT.

1,206,831.

Specification of Letters Patent.

Patented Dec. 5, 1916.

Application filed December 11, 1913. Serial No. 805,931.

To all whom it may concern:

Be it known that I, LOUIS J. FLINT, a citizen of the United States of America, residing at Detroit, in the county of Wayne 5 and State of Michigan, have invented certain new and useful Improvements in Grip-Nuts, of which the following is a description.

My invention belongs to that general class 10 of bolt nuts adapted to fit upon the co-operating bolt in such manner as to reduce the tendency of an accidental disengagement of the two.

To this end my invention consists in the 15 novel method of forming a grip nut, and the product thereof, shown and described and more particularly pointed out in the claims.

In the drawings, wherein like reference 20 characters indicate like or corresponding parts, Figure 1 is a sectional view, showing my improved grip nut upon the bolt; Fig. 2 shows two sections, constituting the grip nut, separated to illustrate the construction, 25 and Fig. 3 is a fragmentary view, showing one of the results of combining the sections in the manner set forth.

In the drawings, it will be seen that the 30 nut is composed of two independent sections, each of which is substantially a complete nut in itself, the two being suitably connected in any preferred manner, as by spot welding, or otherwise, to constitute a single substantially integral nut.

In constructing the nut, any preferred 35 means may be employed to cause a varying fit of the two sections upon the bolt, that is, one section may be standard cut or normal, while the other may vary therefrom and be 40 slightly abnormal, causing it to bind upon the bolt to grip the same, preventing the accidental disengagement by reason of use. As shown, we may assume that the section marked 1 in Figs. 1 and 2 is a standard cut 45 nut, which will engage the bolt with a finger fit, while 2 is a substantially similar nut, or section, attached to the first in such a manner that the sides and bolt opening will coincide, and in which the lead of the thread 50 from one section terminates in such proximity to the beginning of the lead in the other that, in placing the nut upon the bolt, the part 2 will readily engage the thread of

the bolt, and bind or grip thereon, the sections being so cut as to bring about this result when properly assembled. To accomplish this there may be a slight offset in the lead so that the thread of the second section of the nut will impinge, or otherwise bind upon the bolt thread, or the thread of 60 the second nut may be cut at a different pitch or inclination, or at a slightly different spiral inclination, or at a slighter depth to bring about such result. In other words, the binding section of the nut may be cut 65 or arranged in any manner in relation to the coöperating section as to bring about or secure the binding effect, while the first section of the nut may be normal or standard cut to secure easy engagement and holding power. It is obvious that this result 70 may be secured by having both nuts standard cut, but with the lead of the thread in one slightly advanced over the other in the coöperative relation. In such case both the 75 nuts may tend to bind when both the sections take hold of the bolt.

The advantages of my invention will obviously be embodied in any bolt nut comprising two sections secured together, and 80 in which the threads in one section engage the threads of the bolt in a different manner from that in which the threads of the other section engage said threads, causing the nut to bind upon the bolt. 85

In Fig. 3, the fragmentary section shows the variation between the two sections of the nut in one form, exaggerated for the purposes of illustration, 1 indicating that portion of the nut which is engaged with 90 the bolt in the normal manner, and 2 the following portion, whose function is to cause the nut to bind upon the bolt.

It is obvious that this nut may be readily engaged with the bolt, and with a suitable 95 wrench firmly seated, and by similar means may be disengaged without injuring the bolt or nut, so that the two may be readily employed again when desired.

It is also obvious that the thickness of 100 the nut sections may vary as desired without departing from the spirit of my invention, and hence where in the claims I mention nut sections of substantially the same size, the thickness of the sections is not necessarily 105 included.

What I claim as new and desire to secure by Letters Patent is:—

1. An integral grip nut comprising two sections superimposed one on the other, the bolt threads in the two sections being substantially the same form, size, pitch and helix, but having the thread in one section slightly advanced axially in relation to that of the other.
- 10 2. A grip nut comprising two sections superimposed one on the other and operably secured together, the bolt threads in the

two sections being substantially the same form, size, pitch and helix, but having the thread in one section slightly advanced 15 axially in relation to that of the other.

In testimony whereof, I have hereunto signed my name in the presence of two subscribing witnesses.

LOUIS J. FLINT.
